HEATING HORIZONTAL COKE OVENS WITH
VERTICAL HEATING FLUES
Carl Otto, 8 The Beachway, Manhasset, N.Y.
Filed Feb. 24, 1960, Ser. No. 10,606
18 Claims. (Cl. 202—135)

This application is a continuation-in-part of my earlier filed application Serial No. 505,164 filed by me on May 2, 1955, and now abandoned.

This invention relates to horizontal coke ovens with vertical heating flues and particularly to improvements in horizontal coke ovens with vertical heating flues which are adapted to be heated by the combustion of rich gas.

The standard horizontal coke oven battery comprises a plurality of elongated ovens which are spaced apart by coke oven heating walls. Each coke oven heating wall includes two spaced liners with vertical flues extending therebetween. The flues may be interconnecting in a number of different fashions such as by connecting one flue only with the adjacent flue to thereby render what is commonly known as a hairpin flue oven, or the flues may be so connected that all of the flues distributed along one end of the oven are "up flues" whereas all the flues on the other end of the oven are "down flues" to thereby render a "two divided" oven. There are also what is known as four divided ovens and cross over ovens, in the latter of which the flues in one heating wall serve as up flues and the flues in the heating wall on the other side of the coke oven chamber serve as down flow flues.

Regardless of which type of flue arrangement is employed all of the conventional types of coke ovens utilize a principle of introduction of air and gas into the bottoms of a plurality of "up flow" flues which gas air combine and burn to thereby yield heat, which passes through the heating wall liners and into the coke oven chamber where it heats the coal charge and converts it to coke. It is always desirable in coking a charge of coal that the charge be coked at a substantially constant rate at all levels of the charge whereby when any portion of the charge is fully coked the remainder thereof is fully coked to thereby make the entire charge ready to be pushed from the coke oven chamber and thereby render the coke oven chamber ready for subsequent recharging.

There are two types of gas which are normally employed in coke ovens for providing the fuel therefor. There is a rich coke oven gas which has a heating value of approximately 500 to 1000 B.t.u.'s per cubic foot and a lean coke oven gas which has a heating value of approximately 80 to 150 B.t.u.'s per cubic foot. When lean gases are employed the reaction of the gas with the air is usually slow thus yielding a very long flame which may extend from the bottom of the flue to almost its top. With combustion taking place throughout the entire length of the flue the heating throughout the flue is substantially constant and hence the coking rate from the bottom of the oven to the top thereof will be substantially constant. However, when rich gas and air are introduced into a flue of a coke oven the rate of combustion is usually much higher thereby yielding a relatively short flame with a great concentration of heat at the bottom of the oven and substantially lower temperatures towards the top thereof. The relatively poor temperature distribution in rich gas ovens is particularly pronounced in gun flue ovens wherein the rich gas is distributed to the bottoms of the several "up flues" through a ceramic pipe to nozzles located at the bottoms of the vertical heating flues. In such ovens the flame is commonly very short and the temperature at the bottom of the oven is substantially higher than that at the top.

There have been a number of attempts to compensate for the bad temperature distribution in rich gas ovens and

2

particularly in gun flue ovens. The most common expedient for overcoming this difficulty has been to step the thickness of the heating wall liners (stepped wall liners) making the bottom of the liners substantially thicker than the top thereof to thereby retard heat transfer at the bottom as compared with the top to render the temperature in the coke oven chamber substantially constant from bottom to top. While this expedient does work, it will be obvious that what is being done is to reduce the temperature at the bottom of the coke oven chamber so that it will equal the lower temperature at the top of the coke oven chamber. This, however, is not wholly desirable since the coking rate is dependent upon the temperature. Accordingly, by using this expedient the coking rate may well be lower than can be economically achieved at higher temperatures which are not possible when using the stepped wall liner expedient. Furthermore, the cost of thickening the bottoms of the heating wall liners add to the total cost of the coke oven and, in addition, subjects the bottom of the heating wall liner to very high temperatures which hastens the deterioration of the fire bricks.

Still another means of achieving uniform heating in rich gas ovens has been the use of the still or "Christmas tree" oven, as exemplified by U.S. Patent No. 1,901,770, granted to Herman Petsch on Mar. 14, 1933. In these ovens rich gas is introduced at the bottom of the oven and air is introduced at various levels into the heating flue by means of a branched inclined passage through the binder wall. Thus a portion of the gas will combine with the air at different levels and distribute the combustion along the length of the vertical heating flue and thereby tend to eliminate the hot bottom spots prevalent in conventional rich gas ovens. However, the still oven has never been adopted in America due to the fact that the air must be passed up to the various levels in the flue by means of a passage in the heating wall binders which passage tends to weaken the binder and hence the entire coke oven wall structure. Moreover, there is no opportunity for regulating the amount of air introduced at various levels which thereby renders the oven a fairly inflexible device which cannot be adapted to different types of rich gas.

In underjet horizontal coke ovens wherein the gas is introduced at the bottom of the oven through steel pipes, the problem of eliminating the hot spot at the bottom of the oven has been reduced by introducing the gas at two levels, that is by providing high and low burners. By utilizing high and low burners the variation in temperature over the height or length of the flue is reduced as there are two vertically spaced heat sources. However, there still remains substantial variation in temperature of the order of about half that encountered when just a low burner is employed. Moreover, the expedient of high and low burners has never been successful in gun flue ovens due to the fact that the rich gas passing to the upper oven is "cracked" due to the high temperatures at the bottom of the oven to thereby yield carbonization and the depositing of gums and resins at the high burner which clog the burner and reduce the heating value of the gas.

An excellent discussion of these problems is presented in an article entitled Wilputte Issues a White Paper, by Louis Wilputte, May, 1939 issue of Blast Furnace and Steel Plant magazine.

The main object of the present invention is the provision of a new and improved horizontal coke oven utilizing rich gas, which oven will provide substantially uniform heating along the vertical length of the heating flues.

Still another object of the present invention is the provision of a new and improved rich gas gun flue horizontal coke oven which will provide substantially uniform heating along the entire vertical length of the heating wall.

Still another object of the present invention is the provision of a new and improved rich gas horizontal coke oven having heating wall liners of substantially uniform thickness throughout the flues in between the liners with gas and air introducing means which are arranged to elongate the flame to thereby render the heating within the heating wall substantially uniform throughout its height.

Still another object of the present invention is the provision of a rich gas gun coke oven having heating walls with liners of substantially uniform thickness throughout and with flues between said lines having air introducing means therein arranged to render combustion substantially uniform throughout the length of the flues.

In accordance with the present invention, I provide a coke oven battery having a plurality of coke oven chambers spaced apart by heating walls. Each heating wall is made of two liners of substantially uniform thickness throughout the vertical length thereof with a plurality of flues disposed between the heating wall liners. In each flue I provide a gas entrance at the bottom for introduction of rich gas in substantially a wholly vertical direction and I provide means remote from the zone of introduction of the gas for introducing air in an upward path parallel to the path of the gas at two levels. A portion of the air is introduced at the same level as the gas and slowly admixes with the gas to thereby retard total combustion of the gas as it passes up the flue. The remainder of the air is introduced at a higher level. That gas which has not been oxidized by the air by the time it passes the upper level of air introduction will slowly admix with the air introduced in said upper level to continue burning as the gas moves up the flue. Thus combustion will take place along substantially the entire length of the flue and at a relatively uniform rate to thereby render a substantially uniform temperature throughout the length of the heating flue. In accordance with one improvement of said invention, means are provided for regulating the amount of air introduced at the several levels in the heating flue to thereby provide means for effectuating uniform heating regardless of the characteristics of the gas.

The above and other objects, characteristics and features of the present invention will be more fully understood from the following description taken in connection with the accompanying illustrative drawings.

In the drawings:

FIG. 1 is a longitudinal sectional view of a coke oven battery embodying the present invention;

FIG. 2 is a sectional view taken along the line 2—2 of FIG. 1;

FIG. 3 is a sectional view taken along the line 3—3 of FIG. 2;

FIG. 4 is a sectional view taken along the line 4—4 of FIG. 2;

FIG. 5 is a sectional view taken along the line 5—5 of FIG. 1;

FIG. 6 is a schematic vertical sectional view of a coke oven heating wall of present day conventional design;

FIG. 7 is a view similar to FIG. 6 showing a coke oven heating wall in accordance with the present invention with the temperature in the adjacent coking chamber being equal to the temperature in the coking chamber adjacent the heating wall shown in FIG. 6; and

FIG. 8 is a view similar to FIG. 7 showing a heating wall embodying the present invention with the maximum temperature in the heating flues therein equal to the maximum temperature encountered in the heating flues of the heating wall shown in FIG. 6.

FIGS. 1 and 5 generally illustrate a horizontal coke oven battery 10 of well known general construction comprising alternating heating walls 12 and coke oven chambers 14, and regenerator chambers 16 and 18 below the level of said coking chambers and heating walls. The coke oven battery structure 10 is of the well known hairpin flue type of horizontal regenerative coke oven battery adapted especially for burning rich gas. Battery 10 as

illustrative is of the hairpin flue type although other types of flue arrangements may be employed in accordance with the present invention. In the hairpin flue type oven each of the heating walls 12 is formed with numerous non-communicating pairs of vertical flues 20 and 22, the two flues of each pair being connected at the upper ends by passage 24.

A brickwork layer 26 directly beneath the heating walls 12 and coking chambers 14 forms the deck or floor of said heating walls 12 and coking chambers 14 and the roof of the plurality of regenerator chambers 16 and 18. Vertical pillar walls 28 directly beneath each heating wall 12 extend from one side of the battery to the other and similar walls 30 beneath each coking chamber 14 extend from one side of the battery to the other and are spaced in between adjacent walls 28. A row of regenerator chambers 16 or 18 between each adjacent pair of walls 28 and 30 extends from one side of the battery to the other. However, for simplicity of illustration only a few of the regenerators are shown in the drawings. For convenience each of the regenerator chambers disposed to the left of each of the regenerator walls 28 is designated by the reference numeral 18 and each of the regenerator chambers at the opposite side of the pillar wall 28 is designated by the reference numeral 16. Each of the regeneration chambers 16 and 18 extending from one side of the battery to the other is preferably divided by walls 32 into end to end sections and there are about as many walls 32 in each of the regenerator chambers 16 and 18 as there are pairs of hairpin flues in each heating wall 12. The space between each adjacent pair of walls 32 in each regenerator chamber 18 is in direct communication with an adjacent combustion flue 20 and each of the regenerator chambers 16 is similarly divided by a plurality of transverse walls 32 (not shown) into a row of sections, each of said sections in communication with the adjacent combustion flue 22.

In the arrangement shown, each regenerator chamber 16 is connected to an adjacent flue 20 by means of an inclined channel 34 and each regenerator chamber 18 is connected to an adjacent flue 22 by a corresponding inclined channel 36. Each chamber 16 receives air from a subjacent horizontal sole channel 38 when products of combustion flow upwardly through the flues 20 and downward through the flues 22 and discharges products of combustion into the channel 38 when the flow is reversed. Each chamber 18 receives air from a subjacent horizontal sole channel 40 when products of combustion flow upward through the flues 22 and downward through the flues 20 and discharges products of combustion into the channel 40 when the flow is reversed. As is well known, the direction of flow through the flues 20 and 22 is ordinarily reversed at regular intervals, usually a half hour each. As shown, spent products of combustion are discharged into associated sole channel 38 or into the adjacent channels 40 accordingly as the flow is in one direction or the other. Air under pressure may be supplied alternately to the channel 38 and to the channel 40, and air is alternately successively drawn by suction through the channels 38 and 40.

Each heating wall 12 is made up of two spaced vertical brickwork liners 42 and 44 between which extend the hairpin flues 20 and 22 and the connecting passages 24. To define the flues 20 and 22 and the passages 24 vertically extending binder walls 46 and 48 extend between the brickwork liners 42 and 44 at spaced intervals to divide the space between the liners 42 and 44 into the flues 20 and 22. As seen in FIG. 5 the walls 46 do not extend to the top of the flues but are spaced apart therefrom to provide for the passages 24 and the walls 48 extend to the top of the flues to separate one pair of hairpin flues 20-22 from the adjacent pair thereof. In accordance with one feature of the present invention, each of the brickwork liners 42 and 44 is substantially of uniform thickness throughout save for the bottommost

courses of bricks not exceeding about three of standard dimensions in number, but here shown as only one in number, which bottommost courses are thickened to provide for erosion resistance from the action of the pusher. As will be obvious to those skilled in the art, substantially uniformly thick liners 42 and 44 are far more simple to construct than are the stepped liners heretofore employed. It will further be understood as this description proceeds that the use of the uniformly thick liners 42 and 44 can only be effectuated provided the burning or heating in the flues 20 and 22 is substantially uniform throughout the height thereof. As will be shown hereinafter such uniform burning is achieved by the present invention. It will be understood that by the use of the term "uniformly thick liners" or "substantially uniformly thick liners" is meant to convey that the liners 42 and 44 are substantially uniformly thick above about the third course of bricks of standard height of about $4\frac{1}{2}$ inches forming said liners. This is to be contrasted with conventional stepped wall liner construction wherein the wall is divided into three sections of, for instance, six inches, five inches and four inches thickness. Notwithstanding, however, minor variations in thickness of the wall liners made in accordance with the present invention above about the third course of bricks will not render a wall "not substantially uniformly thick." As has been pointed out hereinbefore, the bottommost course must be somewhat thicker than the remainder of the wall. If desired, up to about the bottom three courses of standard sized bricks ($4\frac{1}{2}$ inches high) may be made somewhat thicker.

As shown herein the fuel gas is supplied to the lower ends of the flues 20 and 22 by means of gun flues 50 and 52 which are disposed in the brickwork deck 26 and extend beneath the liners 42 and 44, respectively. The positioning of the gun flues under the liners rather than under the flues as is usual permits the passages 34 and 36 to extend straight upward into the flues 20 and 22 instead of around the gun flues as is the usual construction. This form of construction aids in introducing the air in a straight upward path which is advantageous as will become apparent hereinafter. Branching off at spaced intervals from each gun flue 50 is an inclined passage 54 for conveying gas from the gun flue 50 to a vertically directed nozzle 56 which is located at the bottom of each flue 20 along one side thereof. As shown herein the nozzles 56 are each centrally located with respect to the width of the flues 20 although this is not absolutely necessary to the present invention. Branching off at spaced intervals at each of the gun flues 52 is a plurality of inclined passages 58 for conveying rich gas from the gun flue passages 52 to nozzles 60 disposed at the bottoms of the flues 22. Each of the nozzles 60, like each of the nozzles 56, is oriented to introduce the rich gas into the respective flues in a substantially solely vertical direction. Moreover, each of the nozzles 60 is located preferably relatively close to one side of its flue 22 and centrally of the width thereof. It will be understood as is common practice that gas is alternately fed to the gun flues 50 and 52 depending upon the flow of heating products through the flues 20 and 22. In the event that air and gas is moving upwardly through the flues 20 and downwardly through the flues 22 then rich gas is fed to the nozzles 56 by means of the gun flues 50 and at that time no gas is flowing through the gun flues 52. When the flow is reversed, gas ceases to flow through the gun flue 50 and gas is supplied through the gun flue 52 to the nozzles 60. Although the gun flue construction is preferred, the present invention can also be practiced with other constructions such as underjet ovens.

In accordance with one of the major features of the present invention I have devised means for greatly elongating the flame issuing from a rich gas nozzle 56 or 60 whereby to have substantially continuous burning of the gas as it moves upwardly through the respective flues to thereby provide for uniform heating of the coke ovens

throughout the height thereof. As is pointed out hereinbefore, due to this uniform heating of the coke oven throughout the height thereof the stepping of the liner walls 42 and 44 can be dispensed with to thereby yield 5 uniformly thick liner walls which are simpler to build. The means for achieving this desirable end are shown in detail in FIGS. 2, 3 and 4. Referring now to these figures, each channel 34 extending from the regenerator chamber 16 to the flues 20 is bifurcated at its upper end 10 into two branches 62 and 64 which are substantially solely vertically directed and which open into the bottom of the flues 20 at some distance from the nozzle 56. The two branch passages 62 and 64 preferably open into the flue 20 at opposite sides of a vertical conduit or chimney 66 15 the lower end of which is anchored in the deck 26. The vertically extending passage 68 through the chimney 66 is in direct communication with the passage 34 and preferably extends upwardly a substantial distance above the deck 26 to convey additional combustion air for admixture with the upwardly moving gas at a substantially higher point in the flue. For instance, in a typical coke oven construction wherein the vertically extending flue 20 is approximately eleven feet in height, the top of the chimney may be approximately two feet above the deck 25.

Each flue 22 is similarly provided with a chimney 70 having a vertically extending passage 72 therethrough, which passage is in communication with the air passage 36 at one end and opens in a vertical direction into the 30 flue 22 at the other end. Likewise, the passage 36 extending from the regenerators 18 to the flues 22 are bifurcated into two parts 74 and 76, the two parts 74 and 76 also passing into the flues 22 in substantially a straight vertical direction with no substantial horizontal directional component included.

Thus it will be seen that combustion air introduced into the flues 20 and 22 through the passages 34 and 36 enters said flues through three openings, two of which are at the level of the top of the deck 26 and one of which is disposed substantially above said deck. As will be described in greater detail hereinafter it is due to the vertically spaced introduction of the combustion air into the flues and the fact that the combustion air introduced at the bottom of the flues moves vertically upwardly in a path substantially parallel to the path of the gas introduced through the nozzles that the flame is greatly elongated to provide for uniform heating.

In accordance with another constructional feature of the present invention means is included for regulating the 50 total amount of combustion air introduced into each flue and for regulating the proportion of said combustion air introduced at the bottom of the flue and at the top of the chimney. As shown herein these regulating means are sliding bricks. Referring particularly to FIG. 4, a sliding brick 74 slidably disposed on the top surface of the deck 26 in each of the flues 20 is adapted to be moved into overlying relation with the passage 62 to thereby control the opening of that passage into the flue 20. Likewise a sliding brick 76 is adapted to control the opening of the passage 64 into the flue 20. In a similar fashion sliding bricks 78 and 80 are adapted to control the size of the openings of the bifurcated portions 75 and 77 of the passages 36 into the flues 22. At the top of each chimney 66 in the flues 20 is a sliding brick 82 which is adapted to control the size of the opening from the passage 68 into the flue 20 and, similarly, a sliding brick 84 performs the same function with respect to the tops of the chimneys 70 in the flues 22. With respect to each flue 20 the total volume of combustion air introduced therein can be controlled by properly manipulating the sliding bricks 74, 76 and 82 and, further, the distribution of the air between that introduced at the bottom of the flue and that introduced at the top of the chimney can be controlled by controlling the relative sizes of the openings 75 at the bottom of the flue and the top of the chimney.

Similar manipulation of the sliding bricks 78, 80 and 84 in the flues 22 can achieve the same result for upward flow of combustion air therein.

In operation and assuming (1) that air and gas are being introduced into and moving upward in the flues 20 and the products of combustion are moving downwardly and out through the flues 22; (2) that gas is being introduced in a strict vertical direction through the nozzle 56; and (3) that sliding bricks 74, 76 and 82 are all properly adjusted for the proportioning of the introduction of air at the bottom and top of the chimney 66, then the air introduced at the bottom of the chimneys through the bifurcated portions 62 and 64 of the air passages 34 will move upwardly parallel to the gas ejected from the nozzle 56. With the air and the gas moving in parallel paths, i.e. substantially laminar flow, there will not be complete mixing of the air and the gas but only a partial admixing thereof, some of the gas remaining uncombined with the air. This fractional combination of air and gas is enhanced by the fact that the volume of air introduced at the bottom of the flue is insufficient to combine with the total volume of gas. Thus there will only be a partial or incomplete burning of the gas as it moves upwardly in the area of the chimney. Moreover, this burning will be continuous as there is constant admixing of the streams of air and gas as they move parallel upwardly through the flue 20 in laminar flow. However, as the additional stream of air is added at the top of the chimney this air will be available for further combination with the gas as it continues moving upwardly through the flue 20. Again, as in the zone of the chimney, this mixing, due to the fact that the streams of air and gas move in parallel directions, will be gradual so that the combustion will continue throughout substantially the entire length of the flue. To maintain the streams of air and gas flowing in parallel paths, it is preferable that turbulence in the streams be kept to a minimum. Thus, the flame emanating from the nozzle 56 extends for substantially the full length or height of the flue 20 in much the same fashion as is achieved with lean gas. Hence, with proper regulation of the volume of air introduced into the flues 20 and with proper regulation of the relative amounts introduced at the bottom and top of the chimney, complete combustion of the gas can be achieved by the time the stream reaches the top of the flue 20 and throughout the length of the flue combustion will continue. With proper regulation this combustion can be substantially uniform throughout to thereby yield a substantially constant temperature throughout the entire height of the flue 20. Temperature differences throughout flues of the described construction can be readily kept to less than 30° C. as compared with present day differences of as much as 150° C. With the temperature within the flue 20 being substantially uniform throughout the length thereof there is no need for the graduating of the thickness of the liner walls 42 and 44 as is generally done in prior art constructions to thereby permit the use of the uniformly thick liner walls heretofore mentioned. Naturally, the products of complete combustion in the flue 20 will pass through the passage 24 and downwardly through the associated flues 22 and out through the regenerators 18 and sole channel 40. In addition to regulating the combustion as described above, the total volume of gas and air flowing through each of the flues may be regulated by suitable means such as sliding bricks located at the tops of the flues or in the passages 24.

After due passage of time, the flow will be reversed to introduce air and gas upwardly in a substantially strict vertical direction through the flues 22 and downwardly through the flues 20. Naturally, regulation of the volume of combustion air available to flues 22 can be achieved by manipulation of the sliding bricks and, further, the relative amounts of air introduced at the bottom and top of the chimney can also be so regulated. Again, as is true with upwardly flow through the flues

20, with proper proportioning of the volume of air at the bottom and top of the flue 22 and with the strict vertical passage of the streams of air and gas through said flue 22 the length of the flame in the flue 22 can be substantially the full length or height of the flue 22 to yield uniform heating throughout the height of the heating wall. Naturally, with the products of combustion moving upwardly through the flue 22 they will pass through the passages 24 and down through the flues 20 and out through the regenerators 16 and the sole channels 38.

Hence, it will be seen that by utilizing the features of the present invention and particularly by spacing the zones of air and gas at the bottom of the flues and by directing said streams of air and gas in a parallel upward direction to inhibit admixing thereof the elongated flame can be achieved to thus yield substantially uniform heating.

With the substantially uniform burning throughout the height (or length) of the flues the substantially uniformly thick wall liners 42 and 44 may be employed. The thickness of these wall liners may be equal to the minimum thickness of previously used stepped wall liners, approximately four inches, in which event, if the same amount of gas is consumed as in conventional coke ovens, the temperature within the coke ovens will be higher to thus yield a more rapid coking of the coal charge or, the amount of fuel consumed may be reduced to reduce the temperature in the coking chamber to that normally encountered in present day ovens to thus yield a coking rate the same as is presently achieved but with less fuel and with lower flue temperatures. As the deterioration of the liner walls is dependent in part on temperature, the life of the liner walls under the reduced temperature conditions will be substantially increased.

For example, as shown in FIG. 6, in a present day conventional gun flue hairpin oven having a standard stepped liner walls of the dimensions six inches thick at the bottom, five inches thick in the middle and four inches thick at the top, to maintain the present day standard coking rate of one inch per hour in a seventeen inch wide oven, it is necessary to have the temperature at the bottom of the flue approximately 1420° C. which results in the temperature at the middle of the flue being about 1350° C. and at the top of the flue 1280° C. With these flue temperatures in a stepped liner wall construction the temperature of the oven side of the liner walls will be uniformly about 1000° C. and this will yield the standard coking rate of about one inch per hour.

However, as shown in FIG. 8, in an oven of my novel construction as described herein, and having substantially uniformly thick liner walls of about four inches thickness, if the maximum temperature in the flue is maintained at the same level as the maximum temperature in the flue of a conventional oven, namely 1420° C., the temperature throughout the flue in my oven will be approximately 1420° C. to thereby yield a substantially uniform temperature of about 1070° C. on the coke oven chamber side of the uniformly thick liner walls. This higher coke oven chamber temperature will result in a faster coking rate, which increased coking rate will result in a reduction in coking time in a seventeen inch coking chamber of about an hour and a half.

In the alternative, as shown in FIG. 7, in a coke oven battery of my novel construction, the coking rate can be maintained at the standard value of one inch per hour by lowering the maximum temperature in the heating flues. I have found that to maintain the temperatures on the coking chamber side of the liner walls at 1000° C., the maximum temperature inside the heating flues, assuming substantially uniformly thick liner walls of four inches, will be only about 1280° C., resulting in a net reduction of flue temperature of about 140° C. This substantial reduction in flue temperatures will result in

a substantially longer life for the wall liners and in a saving in fuel.

While I have herein shown and described the preferred form of the present invention, it will be understood that various changes and modifications can be made therein within the scope of the appended claims without departing from the spirit and scope of this invention.

What I claim is:

1. A horizontal coke oven battery, comprising a plurality of spaced apart coke oven chambers and a plurality of heating walls disposed therebetween, each of said heating walls comprising a pair of spaced apart heating wall liners and a multiplicity of transversely extending binders defining a multiplicity of vertically extending flues, each of said flues having at the bottom thereof means for introducing therein in substantially solely a vertical direction rich gas, means horizontally spaced from said gas introducing means for introducing a stream of combustion air, said last mentioned means including an air passage having a substantially solely vertically extending end portion communicating with the bottom of said flues and a substantially solely vertically directed chimney overlying a part only of said vertically extending end portion of said air passage for conducting air to said flue at a level substantially above the bottom of said flue, said chimney being spaced from said heating wall liners.

2. A horizontal coke oven battery as defined in claim 1 further comprising a sliding brick in each of said flues adapted to overlie the part of said end portion of said air passage which is out of underlying relation with said chimney for adjusting the opening hereof into said flue, and a second sliding brick in each of said flues adapted to overlie the top of the chimney therein for adjusting the chimney opening into said flue.

3. A horizontal coke oven battery, comprising a plurality of spaced apart coke oven chambers and a plurality of heating walls disposed therebetween, each of said heating walls comprising a pair of spaced apart heating wall liners and a multiplicity of transversely extending binders defining a multiplicity of vertically extending flues, each of said flues having a substantially solely vertically directed nozzle at the bottom thereof for introducing a vertically directed stream of rich gas therein, a refractory deck underlying said coke oven chambers and heating walls, said deck having a plurality of air passages extending therethrough into said flues for conducting air thereto, the end portions of said passages being substantially solely vertically extending and being horizontally spaced from their associated nozzles, and a vertically extending chimney in each of said flues spaced from said heating wall liners and overlying a central part of the end portion of its associated air passage and leaving uncovered two side parts thereof, said chimney having its upper end spaced a substantial distance from the bottom of said flue.

4. A horizontal coke oven battery, comprising a plurality of spaced apart coke oven chambers and a plurality of heating walls disposed therebetween, said heating walls each including a pair of spaced substantially uniformly thick wall liners having a multiplicity of vertically extending hairpin flues disposed therebetween, each of said flues having a substantially solely vertically directed nozzle at the bottom thereof for introducing a vertically directed stream of rich gas thereto, a refractory deck underlying said coke oven chambers and heating walls, said deck having a plurality of air passages extending therethrough into said flues for conducting air thereto, the end portion of each of said passages being substantially solely vertically extending and being horizontally spaced from its associated nozzle, and a vertically extending chimney in each of said flues overlying a central part of the end portion of its associated air passage and leaving uncovered two side parts thereof, said

chimney having its upper end spaced a substantial distance from the bottom of said flue.

5. A horizontal coke oven battery as defined in claim 4, further comprising a pair of sliding bricks adapted to overlie said side parts of said air passage opening, and a sliding brick adapted to overlie the upper end of said chimney.

6. A horizontal coke oven battery comprising a plurality of spaced apart coke oven chambers and a plurality of heating walls disposed therebetween, said heating walls having a multiplicity of vertically extending flues therein, each of said flues having a regenerator disposed beneath said chambers and heating walls, a refractory deck separating said regenerator from said coke oven chambers and said heating walls, each of said heating walls including a pair of spaced wall liners and a multiplicity of vertically extending flues disposed therebetween, a gun flue for substantially each liner, said gun flues extending horizontally through said deck in substantially vertical alignment with said liners, a substantially solely vertically directed nozzle at the bottom of substantially each of said flues, passage means for connecting said nozzles to said gun flues, said deck having a multiplicity of substantially solely vertically extending passages therein between said gun flues for connecting said regenerator to the bottoms of said flues for passing preheated combustion air to said flues in a substantially solely vertical direction, the area of communication of each of said passages with the bottom of its associated flue being horizontally offset from the nozzle therein, and a substantially solely vertically extending chimney in substantially each of said flues, each chimney being disposed in spaced relation with said heating wall liners over a portion only of said area of communication so that the remainder of said area of communication is out of underlying relation with said chimney, the upper ends of said chimneys being located a substantial distance above the bottoms of said flues.

7. A horizontal coke oven battery as defined in claim 6, wherein said wall liners are of substantially uniform thickness.

8. A horizontal gun flue coke oven battery, comprising a plurality of spaced apart coke oven chambers and a plurality of heating walls disposed therebetween, each of said heating walls comprising a pair of spaced apart heating wall liners and a multiplicity of transversely extending binders defining a multiplicity of vertically extending flues, each of said flues having an upwardly directed nozzle for introducing rich gas therein, a refractory deck underlying said coke oven chambers and heating walls, said deck having a plurality of air passages extending therethrough into said flues for conducting air thereto, the end portions of said passages being upwardly directed and being horizontally spaced from their associated nozzles, and a vertically extending chimney in each of said flues spaced from said heating wall liners and overlying a central part of the end portion of its associated air passage and leaving uncovered a portion thereof, said chimney having its upper end spaced a substantial distance from the bottom of said flue.

9. A horizontal gun flue coke oven battery as defined in claim 8, further comprising a sliding brick in each of said flues adapted to overlie the part of said end portion of said air passage which is out of underlying relation with said chimney for adjusting the opening thereof into said flue, and a second sliding brick in each of said flues adapted to overlie the top of the chimney therein for adjusting the chimney opening into said flue.

10. A horizontal gun flue coke oven battery, comprising a plurality of spaced apart coke oven chambers and a plurality of heating walls disposed therebetween, said heating walls each including a pair of spaced apart heating wall liners of substantially uniform thickness with a multiplicity of vertically extending flues disposed therebetween, each of said flues having an upwardly directed nozzle for introducing rich gas therein, a refractory deck

underlying said coke oven chambers and heating walls, said deck having a plurality of air passages extending therethrough into said flues for conducting air thereto, the end portions of said passages being upwardly directed and being horizontally spaced from their associated nozzles, and a vertically extending chimney in each of said flues overlying a central part of the end portion of its associated air passage and leaving uncovered a portion thereof, said chimney having its upper end spaced a substantial distance from the bottom of said flue.

11. A horizontal coke oven battery, comprising a plurality of spaced apart coke oven chambers and a plurality of heating walls disposed therebetween, said heating walls each including a pair of spaced apart substantially uniformly thick wall liners having a multiplicity of vertically extending flues disposed therebetween, each of said flues having a substantially solely vertically directed nozzle at the bottom thereof for introducing a vertically directed stream of rich gas thereto, a refractory deck underlying said coke oven chambers and heating walls, said deck having a plurality of air passages extending therethrough into said flues for conducting air thereto, the end portion of each of said passages being substantially solely vertically extending and being horizontally spaced from its associated nozzle, and a vertically extending chimney in each of said flues spaced from said heating wall liners and overlying a central part of the end portion of its associated air passage and leaving uncovered two side parts thereof, said chimney having its upper end spaced a substantial distance from the bottom of said flue.

12. A horizontal gun flue coke oven battery, comprising a plurality of spaced apart coke oven chambers and a plurality of heating walls disposed therebetween, said heating walls each including a pair of spaced apart heating wall liners of substantially uniform thickness with a multiplicity of vertically extending flues disposed therebetween, each of said flues having an upwardly directed nozzle for introducing rich gas therein, a refractory deck underlying said coke oven chambers and heating walls, said deck having a plurality of air passages extending therethrough into said flues for conducting air thereto, the end portions of said passages being upwardly directed and being horizontally spaced from their associated nozzles, and a vertically extending chimney in each of said flues spaced from said heating wall liners and overlying a central part of the end portion of its associated air passage and leaving uncovered a portion thereof, said chimney having its upper end spaced a substantial distance from the bottom of said flue.

13. A horizontal coke oven battery, comprising a plurality of spaced apart coke oven chambers and a plurality of heating walls disposed therebetween, said heating walls comprising a pair of spaced apart heating wall liners and a multiplicity of transversely extending binders defining a multiplicity of vertically extending flues, each of said flues having at the bottom thereof means for introducing therein in substantially solely a vertical direction rich gas, said rich gas introducing means being located substantially equidistant from its associated heating wall liners and adjacent one of its associated binders, means horizontally spaced from said gas introducing means for introducing a stream of combustion air into each of said flues, said last mentioned means including an air passage having a substantially solely vertically extending end portion communicating with the bottom of said flues adjacent the other of the binders defining the flues, and a substantially solely vertically directed chimney overlying the central part only of said end portion of said air passage and leaving the side parts thereof in direct communication with the bottom of said flue whereby air will be introduced into the bottom of the flue and at a level substantially above the bottom thereof, said chimney being spaced from said heating wall liners.

14. A horizontal coke oven battery, comprising a plurality of spaced apart coke oven chambers and a plurality of heating walls disposed therebetween, said heating walls comprising a pair of spaced apart heating wall liners and a multiplicity of transversely extending binders defining a multiplicity of vertically extending flues, each of said flues having at the bottom thereof means for introducing therein in substantially solely a vertical direction rich gas, said rich gas introducing means being located substantially equidistant from its associated heating wall liners and adjacent one of its associated binders, means horizontally spaced from said gas introducing means for introducing a stream of combustion air, said last mentioned means including an air passage having a substantially solely vertically extending end portion communicating with the bottom of said flues adjacent the other of the binders defining the flue, and a substantially solely vertically directed chimney overlying the central part only of said end portion of said air passage and leaving the side parts thereof in direct communication with the bottom of said flue whereby air will be introduced into the bottom of the flue and at a level substantially above the bottom thereof, said chimney being connected to said other of said binders and being spaced from said heating wall liners.

15. A horizontal coke oven battery, comprising a plurality of spaced apart coke oven chambers and a plurality of heating walls disposed therebetween, each of said heating walls comprising a pair of spaced apart heating wall liners and a multiplicity of transversely extending binders defining a multiplicity of vertically extending flues, each of said flues having at the bottom thereof means for introducing therein in substantially solely a vertical direction rich gas, means horizontally spaced from said gas introducing means for introducing a stream of combustion air, said last mentioned means including an air passage having a substantially solely vertically extending end portion communicating with the bottoms of said flues and a chimney having a substantially solely vertically directed upper end portion for introducing air into said flue at a level substantially above the bottom of the flue in substantially solely a vertical direction, said chimney being spaced from said heating wall liners.

16. A horizontal coke oven battery as defined in claim 15, further comprising a sliding brick adapted to overlie said upper end of said air passage, and a sliding brick adapted to overlie the upper end of said chimney.

17. A horizontal coke oven battery, comprising a plurality of spaced apart coke oven chambers and a plurality of heating walls disposed therebetween, said heating walls each including a pair of spaced substantially uniformly thick wall liners having a multiplicity of vertically extending flues disposed therebetween, each of said flues having a substantially solely vertically directed nozzle at the bottom thereof for introducing a vertically directed stream of rich gas thereto, a refractory deck underlying said coke oven chambers and heating walls, said deck having a plurality of air passages extending therethrough into said flues for conducting air thereto, the end portion of each of said passages being substantially solely vertically extending and being horizontally spaced from its associated nozzle, and vertically extending chimneys associated with said flues for conducting combustion air to said flues, the upper ends of said chimneys being a substantial distance above the bottoms of said flues and being substantially solely vertically directed.

18. A horizontal coke oven battery, comprising a plurality of spaced apart coke oven chambers and a plurality of heating walls disposed therebetween, said heating walls each including a pair of spaced substantially uniformly thick wall liners having a multiplicity of vertically extending flues disposed therebetween, each of said flues having a substantially solely vertically directed nozzle at the bottom thereof for introducing a vertically

directed stream of rich gas thereinto, a refractory deck underlying said coke oven chambers and heating walls, said deck having a plurality of air passages extending therethrough into said flues for conducting air thereinto, the end portion of each of said passages being substantially solely vertically extending and being horizontally spaced from its associated nozzle, and vertically extending chimneys associated with said flues for conducting combustion air to said flues, the upper ends of said chimneys being a substantial distance above the bottoms of said flues and being substantially solely vertically directed, said chimneys being spaced from said heating wall liners.
